AUTOMATIC TRAIN PIPE CONNECTER

Joseph Robinson, New York, N. Y., assignor of
one-half to Roy M. Wolvin, Montreal, Quebec,
Canada

Application January 21, 1929, Serial No. 333,868
Renewed January 6, 1934

8 Claims. (Cl. 285—58)

This invention relates to automatic train pipe connectors and has among its objects to simplify the construction and reduce the cost of manufacture of these devices. In carrying this object out I provide an improved support on which is mounted a coupling head having characteristics peculiarly important in carrying out the object of my invention.

Heretofore practically all automatic train pipe connectors have been constructed with a rigid bracket extending from the car coupler lug downwardly beyond the horizontal center line of the connector, a stem leading from the head rearwardly through or around the bracket, and a coiled spring at the rear of the bracket, or between the bracket and the head, for extending the head and for co-acting with the bracket to support the head in the normal horizontal position. In some constructions, the coupling head is supported against vertical downward movement by a rod or a chain, but in every connector that I know of which has operated with any degree of success there is a considerable distance between the head and the bracket compared to such distance in the present invention. Similarly the coupling heads used in these prior constructions have gathering means of length considerably greater than the length of the gathering means employed in my invention. There is an important relationship between these dimensions in the automatic connector I have produced. The greater the distance between the coupling head and the bracket, and the longer the guides or prongs of the coupling head, the more difficult it is to align the heads in coupling—see Figure 6. In the present invention the pivotal point of the head is, as usual, at the bracket, but the bracket is very near the rear side of the coupling head. The gathering means are preferably of the pin and funnel type and are very short or shallow. They are preferably of the pin and funnel design for the reason that in the supporting device of the present invention no means is provided for resisting lateral movement of the coupling head, an advantage which will later be explained. Therefore, the pin and funnel arrangement lends itself well to the successful carrying out of the objects of this invention for the reason that once the guide pin enters the funnel the heads must come to alignment. The pin cannot get out of the funnel, and as the heads move to final engagement they necessarily are forced into alignment notwithstanding the absence of resistance to lateral movement of the head. Therefore the particular form of coupling head illustrated be-

comes an important part of the combination of elements by which the objects of this invention are achieved. Ofttimes in service car couplers "slip by", and it is necessary that the coupling heads of the connectors shall be capable of a wide range of lateral movement without injury to any of the connector parts. When "slip bys" occur, it is not uncommon for the connectors to be forced to a position at right angles to the track. In present connectors the result is damage to the coupling head, or to the stem leading from the head through the bracket, or damage to the bracket itself. Ofttimes damage to all these parts occurs. The novel form of the universal joint of the present invention (Figures 1 and 2) permits a wide range of vertical and lateral movement to the coupling head which completely protects the connector against damage in "slip bys".

A further advantage resulting from this freedom of movement in the universal joint is the reduction of stresses in the train pipe hose when the connector head is pushed around to one side (especially to the left, facing the car) in "slip bys". In such swinging of the connector, the hose is, with present connector types, considerably stretched. This is due to the relatively great distance from the coupling head face rearwardly to the center of the universal joint in existing connectors. With this distance shortened as in the present invention, the coupling head may, without strain on the hose, move to any position required by the conditions of service.

Another desirable advantage, and one applying especially to the purposes of the present invention, is that of passing the conduit through the coupling head at an angle of 45° to the track. The peculiar advantage arising therefrom for this invention is, first, it is desirable to use in this invention a compact buffer spring of nominal resistance. If the rearward force on the connector head due to the fluid pressure is considerable, it would, because of the position of the spring in this invention, overcome the spring's resistance, unless the spring is heavy. If a heavy spring is used, the object of simplicity and compactness, with low manufacturing cost, constituting one of the objects of the present invention, would be defeated. By passing the conduit through the head at angle of 45° to the track the resistance of the fluid pressure carried is greatly reduced as respects its tendency to kick the connector heads apart. The result is that the use of a relatively light spring is permitted with excellent results. On many cars there is not

room to place a heavy spring in the position shown.

In passing the conduit through the coupling head at the angle mentioned I provide an improved form of stem for the head which will later be more fully described.

Other and further objects and advantages of the invention will be hereinafter set forth and the novel features thereof defined by the appended claims.

10 In the drawings:

Figure 1 is a side elevation of my invention as it would appear applied to a car. In this view a part of the car coupler and a part of the train pipe hose are broken away.

15 Figure 2 is a plan view on the line 2—2 of Figure 1.

Figure 3 is a front elevation of the bracket or supporting means of a part of my invention, and

20 Figure 4 is a side elevation of a modification of the supporting means of my invention.

Figure 5 is a front view of such modification with the spring omitted.

25 Figure 6 is a diagrammatic plan view illustrating the advantages of the short prong and shallow funnel of the coupling head of my invention, in combination with the short hook up between the universal joint and the coupling head, over the long hook up between these parts.

30 Figure 7 is a detail side elevation of the forward end of the stem.

Referring now to the drawings: My invention is attached to the customary lug 8 of the car coupler 9 by means of a bracket or base A, the upper end of which is turned to pass through an opening in the lug to threadingly receive a nut 10. A vertically extending groove 11 is provided in the lug in which the upper end or neck 12 of the base rests and is securely locked by the nut 10. The arrangement prevents movement of the base with respect to the lug. A forked arm or bracket 14 is provided to the base at 15 and extends downwardly therefrom. Pivoted or otherwise secured within the fork of the arm 45 and extending rearwardly therefrom through a spring seat 16 forming a part of the base A, I provide a tie-rod 17 having a seat 18 for a spring. Around the tie-rod and between the seats 16 and 18 I mount a coiled spring 19 preferably of the 50 volute type. The purpose of this spring is to resist rocking movement of the arm 14 longitudinally of the car, and to hold the arm at the limit of its forward movement, such limit being determined by the position of the nut 20 on the tie-rod 17.

55 At its lower end the rocker arm or bracket 14 is hooked into an opening or seat 21 (Figure 2) in the rear end of the stem B of my invention. The projection 22 at the lower end of the arm forms a seat or support for supporting the rear end of the stem B on the arm. The arm is preferably round in cross section where it contacts with the wall 23 of the stem, the contacting surfaces of this wall, and of the arm, being flared in opposite directions as shown to permit the stem to move freely on the arm.

70 The arrangement of the parts of my improved support produces a universal joint of extreme simplicity, in which the pivot point of the head C on the bracket 14 is, for the important reasons heretofore pointed out, located a distance to the rear of the head that is less than one-half the distance covered by the lateral spread of the gathering means of the head—see Figures 2 and 6.

The forward enlarged end of the stem B is rectangular in cross section and is hollow, as shown particularly in Figures 2 and 7, and the face 24 thereof is disposed at an angle of approximately 45° to the longitudinal direction of the 5 connector. The stem fits snugly in a complementary opening in my improved coupling head C, later more fully described, and is rigidly secured therein by means of rivets 25, or other suitable securing means. Mounted in the forward hollow 10 end of the stem B, and with its face disposed at an angle of 45° to the longitudinal direction of the connector, and preferably flush with the face 24 of the stem, I mount a suitable conduit 26 having in its forward end the customary resilient 15 gasket not shown. The conduit is removably held in the stem by means of a suitable spring actuated or other form of plunger 27, such as shown in my co-pending application Serial No. 248,917 filed January 23, 1928 for improvements in automatic train pipe connectors.

At one side the conduit is provided with a perforated lug 28 through which the plunger 27 extends to lock the conduit in place. As aforesaid, the forward end of the stem B is of rectangular shape in cross section—see Figure 7. It is slotted at 29 to receive the projection 28 of the conduit, and is provided with a neck or projection 30 which lies in advance of the front face of the coupling head C. Against the inner machine finished wall 31 of this projection, the forward end of the conduit 26 lies, and is positioned thereby. The customary train pipe hose 32 is suitably secured to the rear end of the conduit as by the usual clamp 33.

35 My improved coupling head C consists of a shallow funnel 34 disposed on one side of the longitudinal center line of the connector, and a prong or pin 35 disposed on the opposite side of the longitudinal center line of the connector. The funnel and the pin are preferably integral, and the latter lies in advance of the front face of the former. The pin is slotted as at 36 (Figure 1) throughout the greater portion of its length to minimize the adverse effect of snow and ice that 40 might accumulate in the funnel 34. A machined seat 37 is formed at the base of the funnel to receive the machined forward end of the pin 35 as shown in Figure 2. In this view the stem B and conduit 26 are illustrated in the coupled position. Preferably the pin 35 is very short, and the funnel 34 is of corresponding shallow depth. This 45 construction provides greater ruggedness and greater strength; it facilitates exclusion of snow and ice from the funnel, and increases the coupling capacity of opposing connectors under all conditions of disalignment in service. The advantages of a short pin, and a shallow funnel, and their contribution to the objects of this invention, in co-operation with the position of the 50 universal joint formed between the stem B and the lower end of the arm 14, are especially important. At 38 in Figure 6 is shown the point at which a longer prong or pin would contact with a wall of the funnel 34 under a given condition 55 of disalignment between connector heads. In the same view, it will be noticed that the point of contact at 38 is considerably inside of the universal joint 39, which is located, as in present connectors, a considerable distance rearwardly of 60 the head. The effect of further movement of the connector heads towards each other would be to push the heads around to one side, causing a coupling failure. However, if the universal joint is located at 40, as in the present invention, even 65

the long prong would strike outside of the universal joint and hence would cause the coupling heads to swing into the coupled position. By shortening the length of the pin 35, and lessening the depth of the funnel 34, as illustrated, and by locating the universal joint at 40, even considerably greater disalignment between heads than that indicated in Figure 6 can be had without failure to couple.

10 To support the coupling head C in the normal horizontal position, I employ a chain or other suitable member 41 which is hooked into the head as at 42 and into a projection 43 on the base A.

In Figures 4 and 5 a modification of my improved support is illustrated. This consists of threading the base A' into the underside of the car coupler as at 44, and providing the base with a rearwardly extending finger 45 which passes through an opening in the arm 14' and extends along a horizontally disposed seat 46 formed on the upper end of the arm. The arm is pivoted to the base A' at 14'. On the seat 46 a vertically disposed volute spring 47 is mounted, and is anchored in position by a tie-rod 48 which extends downwardly through the spring, through the seat, and is hooked over the rear end of the projection 45 for rocking movement thereon. For supporting the coupling head C in the normal horizontal position I provide a rod 49, one end of which is hooked into the coupling head at 50 and the other end 51 of which extends loosely around the arm 14' as shown. This end 51 of the rod is provided with an elongated opening so that by turning the rod to one side it may be slipped upwardly over the projections 52 which maintain it in proper vertical position on the arm 14'.

Figure 6 has been included in the drawings to illustrate generally the advantage of locating the mounting, as at 40, closer to the head of the connector rather than removed therefrom as indicated at 39. As set forth above, with the connector heads supported at 39, and the cars to be coupled on a curve of the track, it may occur that the point of contact of the pin 35 with the head 34 is disposed on that side of the straight line connecting the mountings 39 which is opposite from the center of the track curve. Such a contact between the connector heads would result in a "slip by" which would prevent the coupling of the heads. By locating the mounting closer to the head than as shown at 39, the disadvantage just noted is less likely to occur. There is, however, a critical point, which may be determined by taking into consideration the maximum curvature encountered in railway service, such that if the mounting is located between the said critical point and the head, a slip by is impossible. This is amply described in Figure 6, wherein, with the mounting located at 40, the initial point of contact between the pin 35 and the funnel 34 is disposed on the same side of the line 40—40 as the center of the curve of the track. In the shallow funnel and short pin construction which I have provided, I have located the mounting 40 back from the head a distance less than one-half the gathering range of the head. This distance, it will be noted by proper measurement made in connection with Figure 6, provides for the location of the mounting 40 between the critical point, which would lie approximately in the middle short dash and dot line of said figure were said line extended.

It is apparent then that the desired location of the mounting 40 is above the critical point as viewed in Figure 6 and the location of the desired

point may be defined also to be such that the angle between the axis of the stem of the connector and the line of centers of the desired mountings is smaller than the angle between said axis and the line extending from said mountings to the initial contact point of a pin and funnel.

What I claim is:

1. An automatic train pipe connector comprising in combination, a base fixed to the car coupler of a car, a thrust arm pivoted to the base and extending downwardly therefrom, resilient means adjacent the pivot point of said arm for thrusting the arm forward, and a coupling head supported by the lower end of said arm for rocking movement thereon, said coupling head being placed under pressure by said resilient means when opposing connectors couple up in service.

2. An automatic train pipe connector comprising in combination, a coupling head, a stem extending through the head and rearwardly thereof and provided with a seat, a base rigidly secured to the car coupler of a car, a thrust arm pivoted to the base and extending downwardly therefrom into the seat in said stem, said stem having rocking movement on said arm, means for supporting said head in the normal horizontal position, and resilient thrust means located above said stem and acting against said arm to place said coupling head under pressure when coupled with an opposing connector.

3. An automatic train pipe connector comprising in combination, a coupling head having a stem extending rearwardly therefrom and provided with an opening forming a seat, a base fixed to the car coupler of the car, and having a seat for a spring, a thrust arm pivoted to said base and extending downwardly below said spring seat into the opening in said stem, the contacting surfaces of said stem and said arm being flared in opposite directions, said arm being provided with means for supporting the stem thereon, and a spring mounted in the seat on said base and acting against said arm to place said coupling head under pressure when coupled.

4. An automatic train pipe connector comprising in combination, a coupling head, a member extending through the head and to the rear thereof, a fixed car member, a base rigidly secured to said car member, a thrust arm pivoted to the base and extending therebelow through a seat formed in the rear portion of said stem whereby said stem has rocking movement on said arm, a rod engaging said arm and extending rearwardly therefrom through a part of said base, and a spring surrounding said rod and disposed between the base and said arm and above said stem for thrusting the said arm forward to place said coupling head under pressure.

5. An automatic train pipe connector comprising in combination, a coupling head provided with a stem, means for supporting said coupling head including a base, a pivoted thrust arm anchored to the base and hooked into the stem, the hook connection being universal, whereby said head has universal movement, means for thrusting said arm forward to place said head under pressure, and a conduit mounted in the forward end of said stem at an angle to the longitudinal direction of the connector, whereby the rearward thrust against said arm of the fluid pressure in said conduit will be reduced by a component of the force commensurate with said angle.

6. An automatic train pipe connector comprising in combination, a coupling head, a stem ex-

tending through said head and having a hollow forward end rigidly fixed in the head, the face of said forward end being at an angle to the longitudinal direction of said connector, means for supporting the head for free universal movement, said means including a thrust spring, a conduit positioned in the hollow end of said stem at an angle to the longitudinal direction of said connector, the rearward thrust on said arm due to the fluid pressure in said conduit being less than the forward thrust of said spring, and means for positioning said conduit in said stem and said coupling head and providing for quick removal therefrom when desired.

15. 7. An automatic train pipe connector comprising in combination, a coupling head having a member extending rearwardly therefrom in which is formed a seat, a base for supporting said head, a thrust arm pivoted to the base and extending downwardly therefrom through the seat in said member, flexible means for supporting said head in the normal horizontal position, said means and the connection between said member and said arm being movable to enable the coupling head to swing freely about a vertical axis, resilient means for resisting longitudinal movement of

said coupling head while enabling the said free swinging movement of the head, and gathering means for said head which is adapted to connect with a mating connector to effect coupling of the respective heads under all normal coupling conditions, the initial point of contact of said gathering means on cooperating couplings being located on the same side of the straight line connecting the seats of the respective couplings at which they are normally located under all conditions of track curvature.

8. In an automatic train pipe connector, comprising, in combination, a coupling head having a rearwardly extending portion, a base fixed to the car coupler of the car, an arm pivoted to the base and pivotally engaging the rearwardly extending portion of the head, resilient means between the base and arm acting against said arm to place the coupling head under pressure when coupled, and a rigid member pivotally connected to the head and slidably interconnected with said arm so as to enable the angle of said member with respect to said arm to change as the head moves to coupled position.

JOSEPH ROBINSON.
